(57) **CLAIM**

The ornamental design for a versatile art display, as shown and described.

DESCRIPTION

FIG. 1 is an isometric view of a versatile art display in an assembled position, the versatile art display having a circular shape;

FIG. 2 is a front view of the circular shaped versatile art display in the assembled position, which is a mirror image of the back view, the left side view, and the right side view (not shown);

FIG. 3 is a top view of the circular shaped versatile art display in the assembled position;

FIG. 4 is a bottom view of the circular shaped versatile art display in the assembled position;

FIG. 5 is a top plan view of a base of the circular shaped versatile art display in an unfolded position; and,

FIG. 6 is an inverted, exploded, perspective view of the circular shaped versatile art display, including the base in a folded position, an outer ring portion, an inner ring portion, and a circular cover portion that is to cover the folded tabs of the base, the inner ring portion and the outer ring portion. The even-broken lines in FIGS. 1, 2, 5 and 6 illustrate scored portions of the versatile art display, and form part of the claimed design.
